COOKING STOVE

Henry R. Johannes, Allentown, Pa., assignor to Caloric Corporation, a corporation of Pennsylvania

Filed Apr. 7, 1964, Ser. No. 79,375

Term of patent 14 years

(Cl. D81—4)

FIG. 1 is a front perspective view of a cooking stove embodying my new design, the opposite side being the same as that shown and the back being plain.

FIG. 2 is a top plan view of the same.

The grid lines and parallel horizontal lines indicate contrast.

The dominant features of my design reside in the portions shown in full lines.

I claim:

The ornamental design for a cooking stove, as shown and described.
